Attn:

UNITED STATES PATENT OFFICE.

FREDERICK W. MOHN, OF HOBOKEN, NEW JERSEY.

STAGE APPLIANCE.

SPECIFICATION forming part of Letters Patent No. 467,754, dated January 26, 1892.

Application filed June 20, 1890. Serial No. 356,107. (No model.)

To all whom it may concern:

Be it known that I, FREDERICK WILLIAM MOHN, a citizen of the United States, residing at Hoboken, in the county of Hudson and State 5 of New Jersey, have invented certain new and useful Improvements in Stage Appliances; and I do hereby declare the following to be a full, clear, and exact description of the invention, such as will enable others skilled in the 10 art to which it appertains to make and use the same.

My invention relates to that class of theatrical appliances in which dramatic and scenic effects are produced by means of mechanism 15 operated upon the stage.

The object of my invention is to produce upon the stage mechanism to represent a workshop in full operation, whereby certain stage effects, hereinafter described, can be 20 dramatically represented.

The invention consists of constructions and combinations, all as will hereinafter be described in the specification and pointed out in the claims, reference being had to the accompanying drawings, in which—

Figure 1 represents a front view of the stage with mechanism in proper position; Fig. 2, a side elevation, and Fig. 3 a top plan with the ceiling part of scenery removed.

30 A represents the floor of the stage, and B the scene. This scene B is substantially rectangular in form and is preferably so constructed as to represent two rooms C C', as shown in Fig. 1.

35 a a represent the side walls, and a' the dividing-partition between the rooms, which is provided with a doorway c, constructed in any desired way.

At the back end of room C and running 40 across said room is a power-shaft b⁶, supported by bracket c' and operated from behind the wall a in any convenient manner. Shaft b⁶ is provided near one end with a pulley b⁷, around which passes belt B', said belt also 45 passing around pulley c² on shaft c³, which shaft imparts motion to the fly-wheel b⁵ of engine B³ by the pulley d on the outer end of

said shaft, as clearly shown in the drawings. The belt B' is of greater width than those ordinarily used, for the reason that it is designed to carry the weight of a person at some interval during the play. The engine B³ is constructed in a very simple and inexpensive manner, having only the main features, such as cylinder b, piston b', valve-rod b², crank-shaft b³, and governor b⁴. The opposite end of shaft b⁶ is provided with a suitable gear-wheel c⁴, which meshes with gear c⁵ on shaft b⁸. This shafting b⁸ extends the entire length of both rooms and is supported by brackets or 50 hangers c⁶. At suitable intervals along the shaft b⁸ are two pulleys c⁷ and c⁸, which impart motion to the machines A' A² through the medium of belts, as shown in Fig. 1 of the drawings.

55 In room C', A³ represents work-benches, tables, or the like, and it is designed to represent more especially a finishing or assembling room.

What I claim is—

70 1. A stage structure representing a workshop, having the driving-shaft b⁶, carrying pulley b⁷ and gear c⁴, said pulley b⁷ imparting motion to the engine B by means of belt B', and motion being imparted to shaft b⁸ by 75 means of the gears c⁴ and c⁵, substantially as and for the purpose set forth.

2. In theatrical scenery, the combination, with the stage, of a structure representing a workshop comprising two rooms C and C', 80 room C having the driving-shaft b⁶, which imparts motion to the engine and to shaft b⁸ by means of the belt and gears, as described, said shaft b⁸ also extending through room C', which is provided with work-benches, substantially 85 as shown.

In testimony whereof I affix my signature in presence of two witnesses.

F. W. MOHN.
